FLEXIBLE INDEX STRIP.

Application filed July 14, 1922. Serial No. 574,913.

This invention relates to improvements in flexible index strips and refers more particularly to flexible strips which may be mounted in a frame upon which data is placed where the file is of a relatively temporary character.

Among the objects of the invention are to provide a construction in which flexible line strips are provided in the form of a sheet, and the sheet so scored that the line strips may be easily separated from the sheet by tearing along the scored separations. To provide a construction in which the sheet may be inserted in a typewriter 15 to write any desired data upon the strips prior to separating the strips from the sheet. To provide a flexible line construction which when separated from the sheet may be doubled in order to foreshorten their length 20 and snapped into place behind flanges in a suitable frame.

Fig. 1 is a face view of the frame showing the strips in position. Fig. 2 is a fragmentary face view of the strips in the form of a sheet prior to the strips being separated. Fig. 3 is a view taken along the line 3—3 in Fig. 2. Fig. 4 is a perspective view of one of the strips after being separated from the sheet.

Referring to the drawings, the frame 1 consists of a body of metal which has along its lateral edges flanges or lips 2 extending longitudinally of the frame and riveted to the body portion. The frame is supported in a suitable standard by means of the pintles 3. In Fig. 2 is shown a sheet of strips prior to separation.

The sheet comprises a thin ply or layer of wood veneer faced on both surfaces by a sheet of paper or fabric. The sheet is cut transversely to form line strips as that shown in Fig. 4. In cutting the sheet, the cut is made through one surface and through the wood veneer leaving the paper upon the opposite surface intact. This sheet may be wound on the platen of a typewriter, and identifying data put upon the separate strips. Upon removal from the typewriter, the strips may be torn from the sheet singly, or in numbers, and inserted into the frame by doubling the flexible or resilient strips and inserting them beneath the side flange 2 on the frame.

Strips of this type are easily removable when a change of the data is desired, by inserting an edge beneath the strip and withdrawing its ends from the side flanges of the frame.

The wood veneer with the paper surfacing glued thereto, furnishes a cheap and effective material which takes the print readily and presents a smooth uniform face to the indexing frame. The frames are reversible, and a plurality of frames may be mounted upon a single standard.

I claim as my invention:

1. Flexible index strips in continuous sheet form, comprising wood veneer faced and backed with paper and partially scored in the direction of their depth, thus permitting subsequent separation into individual resilient index strips.

2. Flexible index strips in continuous sheet form, comprising wood veneer having a surfacing of fabric, and partially scored in the direction of their depth, thus permitting subsequent separation into individual resilient index strips.

3. Flexible index strips in continuous sheet form, comprising a continuous sheet of flexible fibrous material partially severed transversely of the length of the sheet and in the direction of the depth thereof, to permit subsequent separation into individual index strips, one face of the partially severed sheet presenting a severed appearance, and the opposite face of the sheet exhibiting an unsevered appearance.

4. Flexible index strips in continuous sheet form, comprising a relatively thin body portion of wood having a surfacing of sheet material adapted to take print readily, said sheet being partially severed in the direction of its depth and transversely of its length to permit easy subsequent separation into individual index strips.

5. Flexible index strips in continuous sheet form, comprising a continuous sheet of flexible fibrous material, partially severed in the direction of its depth transversely of and throughout its length, to permit subsequent separation into individual resilient index strips.

6. Flexible index strips in continuous sheet form, comprising a thin body portion of wood faced and backed with paper and

scored through one paper surface and through the wood surface, leaving the paper upon the opposite surface intact, thus permitting subsequent separation into individual resilient index strips.

7. Flexible index strips in continuous sheet form, comprising a body portion faced

and backed with fabric, and scored in the direction of their depth, said scoring extending through one fabric facing and through the body portion, but terminating short of the other facing.

FRANK D. POWELL.
